ROTARY KILN

Filed Aug. 12, 1929

UNITED STATES PATENT OFFICE

FREDERICK W. CORKILL, OF LOS ANGELES, CALIFORNIA, ASSIGNOR TO PACIFIC COAST BORAX COMPANY, A CORPORATION OF NEVADA

ROTARY KILN

Application filed August 12, 1929. Serial No. 385,274.

This invention has to do with the art of calcination, and is directed to improvements in the construction of rotary kilns, whereby the efficiency of such kilns and the uniformity and quality of the calcined product are greatly increased.

The usual construction of rotary kilns consists of an elongated tubular shell, which is supported upon rollers and is provided with means for introducing material to be calcined at one end of the shell and with means for receiving the calcined material at the opposite end of the shell. Means are provided for rotating the shell at any desired speed, and it is the usual practice to incline the shell slightly away from the end at which the material to be calcined is introduced.

The shell may be heated either externally or internally. It is the usual practice in the use of rotary kilns, however, to supply the heat by means of a burner placed at the outlet end of the shell and adapted to direct a flame through the shell which is counter current to the direction of movement of the material therein.

In the use of kilns of this nature, the material to be calcined is first crushed to a size at which it may be conveniently handled, and the crushed material is introduced into the shell through suitable means, the inclination of the shell and the speed of rotation being such as to produce the desired extent of calcination of the particular material which is being used.

One of the most serious difficulties which has been encountered in the use of kilns of this nature resides in the fact that it is economically impossible to produce a crushed material of uniform fineness in the crushing operation, and since the coarser particles travel through the kiln at a much greater speed than the fine material, these coarser particles which should obviously require a greater time for their complete calcination are in the heating zone a much shorter time than the fine material. It will be seen, therefore, that if the kiln is operated at a speed and at an inclination which will give complete calcination of the coarse material, the finer material is burned. On the other hand,

if the kiln is operated so as to properly calcine the fine material, the coarse material must be separated therefrom after the calcining step and must be subsequently subjected to further calcination.

55

It becomes necessary, therefore, in the usual practice of calcination with rotary kilns to either screen the crushed material before it is introduced into the kiln so that the material has a substantially uniform fineness, 60 or to screen the calcined material after it comes from the kiln and subject the coarse material to a second calcination step. Such an operation in connection with ores in which the calcination must be more or less accurately controlled to obtain the proper results, is obviously impracticable, and in any event is inefficient and expensive.

It is a primary object of this invention to produce a rotary kiln in which the movement 70 of the coarse material through the kiln is retarded, the retarding means being in the form of an obstruction or a plurality of obstructions, which are adapted to permit a substantially uninterrupted passage of fine material through the kiln, but which at the same time retard the movement of the coarse material so that both the fine and the coarse material receive the proper calcination.

It is also an object of this invention to produce a rotary kiln which is provided with baffles, associated with the obstructions mentioned above in a manner such that the flame passing through the kiln is directed into engagement with the material passing over the 80 obstruction, greatly increasing the thermal efficiency of the unit.

Details in the construction of my invention, together with other objects attending its production, will be better understood from 90 the following description of the accompanying drawing, in which

Fig. 1 is a sectional elevation, showing a preferred embodiment of my invention.

Fig. 2 is an end elevation, which may be 95 considered as having been taken substantially in the direction of the arrow 2 in Fig. 1.

Fig. 3 is a sectional elevation which may be considered as having been taken in a plane represented by the line 3-3 in Fig. 1.

100

Fig. 4 is a sectional elevation which may be considered as having been taken in a plane represented by the line 4-4 in Fig. 1, and shows a preferred form of obstruction member, and

Fig. 5 is a sectional elevation which may be considered as having been taken substantially in a plane represented by the line 5-5 in Fig. 1, and illustrates the manner of arranging the baffles in the shell.

More particularly describing the invention as herein illustrated, reference numeral 11 indicates an elongated shell, which is supported by means of rollers 12 and 12', engaging annular channels 13 and 13', mounted upon the outer surface of the shell.

The shell 11 is adapted to receive rotation through the medium of a gear 14, mounted upon its outer surface and engaging a pinion 15, which is adapted to be driven through the medium of a drive shaft 16 from any suitable source of power (not shown).

It will be noted in Fig. 1, as was heretofore pointed out, that the shell 11 is set at a slight inclination, so that the material entering at the end 17 through the hopper 18 will pass downwardly through the shell during its rotation, and will be delivered from the outlet end 19 into a receiving hopper 20, from which it may be delivered onto a conveyor belt, such as is indicated by reference numeral 21.

Means for heating the material within the shell are illustrated as being in the form of a burner 22, which is positioned at the outlet end of the shell, and may be supported in any well known manner.

The inlet end of the shell is shown as being surrounded by a draft chamber 23, which is provided with an outlet pipe 24, which, in turn, may have a natural draft, or may be provided with a fan 25 for providing a forced draft through the shell.

It will be understood by those familiar with the art that the construction so far described is common to rotary kilns such as are now in use, and that the essence of my invention resides largely in means for governing the passage of the material through the kiln. Such means, as has heretofore been pointed out, comprises an obstruction or a plurality of obstructions so constructed and so positioned within the kiln as to permit a substantially uninterrupted passage of the fine material through the shell, and at the same time to retard the passage of the coarse material therethrough. Such obstructions are, in the form illustrated, shown as comprising annular screen members 30, which are positioned in spaced relation with each other throughout the length of the shell, and are retained within the shell in any suitable manner, such as by means of angular straps 31.

It was also mentioned as an object of this invention to provide the shell with baffle means, whereby the hot gases passing through the

shell would be directed into engagement with the material passing over the screens or obstructions. Such baffles are indicated in the drawing by reference numeral 32, and are shown as being in the form of circular plates, supported by angle straps 33, and positioned so that the flame passing through the shell is projected against the baffle and must pass over the material which is held back by the screens or obstructions 31.

In the use of my invention, it will be apparent that the material to be calcined, which is introduced into the shell through the hopper 18 will, during the rotation of the shell, pass downwardly toward the outlet end 19.

The screens 31 permit the passage of the fine material, and it will be understood that the mesh of the screens and the number and arrangement thereof will be governed entirely by the quality and properties of the material which is being calcined in the kiln. The coarse material will, of course, build up behind the screens and its passage through the shell will, accordingly, be retarded, so that it will be completely calcined before it is delivered from the outlet end 19.

It is to be understood that, while I have herein described and illustrated one preferred embodiment of my invention, the same is not limited to the precise construction set forth, but includes within its scope whatever changes fairly come within the spirit of the appended claims.

I claim as my invention:

1. A rotary kiln comprising: an elongated tubular shell; means for rotating said shell; means for injecting a flame into one of said shell; means for introducing material to be calcined into the other end of said shell; a plurality of annular screens mounted in said shell, adapted to permit a substantially uninterrupted movement of fine material through said shell and at the same time retard the movement of the coarse material therethrough; and baffles mounted in the center of said shell adjacent said annular screens for directing the hot gases passing through said shell into contact with the material passing over said obstructions.

2. A rotary kiln comprising: an elongated tubular shell; means for rotating said shell; means for injecting a flame into one end of said shell; means for introducing material to be calcined into the other end of said shell; a plurality of annular screens mounted in said shell adapted to permit a passage of fine material therethrough and a movement of coarse material therover; and a baffle associated with said screens to deflect heat directly upon said coarse material.

In testimony whereof, I have hereunto set my hand at Los Angeles, California, this 30th day of July, 1929.

FREDERICK W. CORKILL. 130
